CLAIM

The ornamental design for a bracelet, as shown and described.

DESCRIPTION

FIG. 1 is a front elevation view of a bracelet showing my new design;

FIG. 2 is a front view of the bracelet;

FIG. 3 is a rear view of the bracelet;

FIG. 4 is a rear right side of the bracelet;

FIG. 5 is a rear left side view of the bracelet;

FIG. 6 is a top view of the bracelet;

FIG. 7 is a bottom view of the bracelet;

FIG. 8 is a rear elevation view of the bracelet;

FIG. 9 is a rear left side perspective view of the bracelet; and,

FIG. 10 is a rear right side perspective view of the bracelet. The broken lines in the drawings showing the text "Joo-JooMee" represent environmental subject matter and form no part of the claimed design.
